ALOIS THOMA, OF NEW YORK, N. Y., ASSIGNOR TO HIMSELF, SAMUEL BROMBERG, AND ARTEMUS W. WILDER, OF THE SAME PLACE.

Letters Patent No. 70,046, dated October 22, 1867.

IMPROVED FURNACE FOR SMELTING IRON ORE.

The Schedule referred to in these Letters Patent and making part of the same.

TO ALL WHOM IT MAY CONCERN:

Be it known that I, ALOIS THOMA, of the city, county, and State of New York, have invented a new and improved Furnace for Smelting Ore; and I do hereby declare that the following is a full, clear, and exact description thereof, which will enable others skilled in the art to make and use the same, reference being had to the accompanying drawings, forming part of this specification, in which—

Figure 1 represents a vertical longitudinal section of my improved smelting-furnace.

Figure 2 is a vertical transverse section of the same.

Figure 3 is a horizontal sectional view of the same, the plane of section being indicated by the line *xx*, fig. 1.

Similar letters of reference indicate corresponding parts.

This invention relates to a new smelting-furnace, for preparing roasted and reduced iron ore for use, and for separating the metal contained therein from the earthy and foreign substances.

By this invention the treatment of ore according to my improved method is completed, the roasting process, as well as the reducing process, having been described in other applications filed herewith.

The invention consists in so arranging the furnace that the ore can be drawn off on two sides, so that it can, from one side, be carried to a suitable furnace for further immediate treatment, while on the other side it can be moulded into ordinary pig iron.

The invention also consists in such an arrangement of the furnace that the carbonic oxide, escaping from the fuel and ore, and uniting with the nitrogen of the blast, thus forming a combustible gas, may be retained for further use, so that the gas thus produced may be employed for the roasting process.

A represents the furnace, built of brick or other suitable material, and lined on the inside with fire-brick in the ordinary manner. The chamber B, formed in the furnace, is of truncated inverted pyramidal form, with an upper part, C, which has upright walls, and which is somewhat shorter and narrower than the upper part of the chamber B. The furnace is set upon a suitable foundation. The lower part of the chamber B has two discharge-channels D D, in each of which a dam-stone, E, is arranged, as is clearly shown in fig. 1. F F are tuyeres of suitable construction, arranged in the walls of the furnace, to conduct the air-blast into the chamber B.

The ore, roasted and freed from arsenic, sulphur, phosphorus, and oxygen, is placed into the chamber B, in alternate layers with coke or charcoal. The fuel is ignited, and air blown through the tuyeres into the furnace, and the iron becomes gradually melted by the enormous heat. The carbonic acid discharged from the burning fuel and melting iron unites with the nitrogen of the air, and the gas thus produced will burn when discharged from the furnace to any other place. To save this gas the upper chamber C is arranged, and is made narrower than the upper part of the chamber B, so as to form a shoulder, *a*, around the inside of the furnace, as shown in the drawings.

It has been noticed that the aforesaid gases do not ascend from all parts of the heap, but generally keep to the wall of the furnace, and rise along the walls. They will therefore, on their passage up, strike the shoulder *a*, and will thereby be conducted into the funnel-shaped ends of horizontal channels *b b*, arranged in the walls of the furnace, as shown more particularly in fig. 3. These channels receive the aforesaid gases, and the same may be carried off to the roasting-kiln, or to any other suitable place, to be used for heating purposes. The channels *b b* have extensions *c* to the outside, closed by blocks *d*. The same are for the purpose of allowing the channels *b* to be cleaned. It is desirable to keep the furnace at work without interruption, and as the channels could not be cleaned unless the gases were discharged for the time, through some other channel, the channels *b* have been connected with upright chimneys *e e*, which are generally closed by plates *f*, but which are opened when the channels are to be cleaned.

The molten iron accumulates at the bottom of the furnace, and can be drawn off, from time to time, through openings in the sides of the dam-stones, which are tapped at intervals. The slag or scoria, floating upon the molten iron, flows over the top of the dam-stones, and is thus discharged.

In charging this furnace the different kinds of ore should be assorted in the ordinary manner, and, if desired, mixed with lime or some other flux, as is at present done in all smelting-furnaces.

I claim as new, and desire to secure by Letters Patent—

1. Arresting the gases arising from smelting-furnaces, so that they may be used for the roasting or some other process, substantially as herein shown and described.
2. Providing a smelting-furnace with two discharge-channels D D, having suitable dam-stones E E, substantially as and for the purpose herein shown and described.
3. The channels b b, when arranged in a smelting-furnace, to retain and carry off the gases, as set forth.
4. The shoulder a, when formed in the charge-chamber of the furnace, in combination with the channels b b, all made and operating substantially as and for the purpose herein shown and described.
5. The channels b b in a smelting-furnace, when combined with the channels e, blocks or doors d, and chimneys e, all made and operating substantially as and for the purpose herein shown and described.

ALOIS THOMA.
